[57] CLAIM

The ornamental design for glass door with brass trim and beveled facets, as shown and described.

DESCRIPTION

FIG. 1 is a perspective view of a full view glass door with brass trim and beveled facets showing my new design; FIG. 2 is a front plan view thereof; FIG. 3 is a right side elevational view, the left side elevational view being a mirror image thereof; FIG. 4 is a bottom plan view, the top plan view being a mirror image thereof; FIG. 5 is a rear elevational view thereof; FIG. 6 is an enlarged side elevational view taken generally along the lines 6—6 of FIG. 2; FIG. 7 is an enlarged fragmentary top plan view of a portion of FIG. 1; FIG. 8 is a perspective mid view of a mid view glass door with brass trim and beveled facets showing my new design; FIG. 9 is a front plan view thereof; FIG. 10 is the right side elevational view, the left side elevational view being a mirror image thereof; FIG. 11 is a bottom plan view, the top plan view being a mirror image thereof; FIG. 12 is a rear elevational view thereof; FIG. 13 is an enlarged side elevational view taken generally along the lines 13—13 of FIG. 8; FIG. 14 is an enlarged fragmentary top plan view of a portion of FIG. 8; and FIG. 15 is a perspective view of a high view glass door with brass trim and beveled facets showing my new design; FIG. 16 is a front plan view thereof; FIG. 17 is the right side elevational view, the left side elevational view being a mirror image thereof; FIG. 18 is a bottom plan view, the top plan view being a mirror image thereof; FIG. 19 is a rear elevational view thereof; FIG. 20 is an enlarged side elevational view taken generally along the lines 20—20 of FIG. 16; and, FIG. 21 is an enlarged fragmentary top plan view of a portion of FIG. 15. The broken lines shown in FIGS. 1, 8 and 15 are for illustrative purposes only and form no part of the claimed design.
